CHILLING APPARATUS

Verney E. Kroft, Pittsburgh, Pa., and Arthur Roe, Newark, N. J., assignors to Carbondale Machine Corporation, Harrison, N. J., a corporation of New Jersey

Application February 5, 1937, Serial No. 124,190.

14 Claims. (Cl. 62—114)

This invention relates to heat interchangers and more specifically to an apparatus for chilling distillates to separate out, for congelation, paraffin wax or the like. This type of apparatus customarily includes one or more series of horizontally disposed pipes arranged at different levels through which the material to be chilled is circulated. The chilling action in these pipes is provided by a volatile refrigerant which is circulated through jackets or evaporator chambers surrounding said pipes.

An object of the present invention is to provide a structure which will insure the delivery of the proper amount of refrigerant to the jackets or evaporator chambers without the need of a refrigerant circulating pump and its necessary appendages, and also a system which is self-regulating.

More specifically the present invention relates to means for controlling the delivery of liquid refrigerant to the cooling jackets or evaporator chambers, and is an improvement over the chilling apparatus disclosed in the co-pending application Serial Number 725,889 filed May 16, 1934. With these and other objects in view, as may appear from the accompanying specification, the invention consists of various features of construction and combination of parts, which will be first described in connection with the accompanying drawings, showing a chilling apparatus of the preferred form embodying the invention, and the features forming the invention will be specifically pointed out in the claims.

In the drawings:

Figure 1 is a side elevation of the improved chilling apparatus having parts thereof broken away.

Figure 2 is a top plan of the chilling apparatus showing parts in section, the section being taken on the line 2—2 of Figure 1.

Figure 3 is a vertical section through the chilling apparatus taken on the line 3—3 of Figure 1; and

Figure 4 is a vertical section through a modified form of the chilling apparatus.

Referring more particularly to the drawings, the improved chilling apparatus comprises a plurality of pipes 1 arranged in vertically spaced tiers, through which the liquid to be chilled circulates. The pipes in each tier are connected by suitable connecting elbows 2 while the pipes in one tier are connected to the pipes in the tier next therebelow by suitable elbows 3 so as to provide a continuous path for the circulation of the liquid to be cooled.

Refrigerant jackets 4 are disposed about the pipes 1, and form evaporator chambers 5 through which a suitable liquid refrigerant, preferably a volatile liquid refrigerant is circulated for chilling the liquid circulating through the pipes 1.

In the preferred form of the invention illustrated in Figures 1 to 3 inclusive, a distributor 10 is provided for controlling the distribution of the volatile liquid refrigerant to the various evaporator chambers 5. The distributor 10 is shown in the form of a vertical standpipe and it has a plurality of partitions 11 therein which correspond to the various vertical tiers of the evaporator chambers. The partitions 11 are located slightly below the lowermost part of the respective tiers of evaporator sections and form pockets in the distributor 10 which are individual to each tier of evaporator chambers.

The volatile refrigerant is supplied from any suitable source (not shown) through a supply pipe 12 to the accumulator 14. The accumulator 14 is mounted at the top of the distributor 10 and opens thereto so that the liquid refrigerant delivered to the accumulator 14 may pass downwardly into the distributor 10.

Each of the pockets in the distributor 10 formed by the various partitions 11 is connected by suitable pipes 15 to the evaporator chambers in the corresponding tier.

Pipes 16 extend through the partitions 11, extending a predetermined distance above and below the partitions and form means of communication between the respective pockets whereby it will be necessary for the liquid refrigerant to rise above the tops of these overflow pipes before any liquid refrigerant will be supplied to the pocket next therebelow. The overflow pipes 16 project upwardly into the pockets a predetermined distance for regulating the height of the liquid refrigerant in the evaporator chambers 5. The overflow pipes project downwardly into the distributor pocket next therebelow, below the upper end of the overflow pipes for the respective pockets.

The overflow pipes 16 are of such height that there will always be left a gas pocket as indicated at 17 in the uppermost portions of the evaporator chambers 5 and these overflow pockets are connected by pipes 18 to the respective pockets in the distributor above the tops of the overflow pipes 16. The evaporated liquid refrigerant thus passes from the evaporator sections 5 through the pipes 18 into the distributor pockets and passes from one distributor pocket, through a gas outlet pipe or tube 19 into the next pocket 55

thereabove and thence onwardly through the series of pockets into the accumulator 14. Any condensation of the gaseous or evaporated liquid refrigerant will pass or fall downwardly into the respective pockets or from the accumulator 14 into the top pocket. A suitable gas take-off as indicated at 20 may be provided.

5 The supply of liquid refrigerant to the accumulator 14 and consequently to the distributor 10 is controlled by the level of the liquid refrigerant in the lowermost tier of evaporating chambers 5 by a float mechanism 21 of any approved type which in turn controls the valve 22. The float mechanism 21 includes the condenser 23 10 which is connected by the pipe 24 to the bottom of the distributor 10 and is placed so that the level of the liquid refrigerant within the tank 23 will be level with the level of liquid refrigerant in the evaporator chambers 5 of the lowermost 15 tier. Since the evaporator chambers 5 in the lowermost tier are the last to receive the liquid refrigerant, and the float structure 21 is arranged so as to open the valve 22 until such time as the level of the liquid refrigerant in the lowermost 20 tier of evaporator sections reaches the desired height, the chilling apparatus will be self-regulated and the quantity of liquid refrigerant delivered thereto will be controlled by the actual 25 needs of the apparatus.

30 Figure 4 of the drawings shows a modified form of the invention and in this modified form the distributor 30 is of sufficient size so that its upper end indicated at 31 may serve the purpose of the accumulator and it has a suitable gas take-off pipe 32 connected thereto. The liquid refrigerant is delivered into the top of the distributor 30 through the supply pipe 33 from any suitable source (not shown). The delivery of liquid refrigerant to the distributor 30 is controlled by a valve 34 which in turn is operated by a float mechanism 35. The float mechanism 35 is connected by a suitable pipe 36 with the bottom of the distributor 30 and it is located so that the level of the liquid refrigerant in the float structure 35 will always be in the same plane as the level of the liquid refrigerant in the lowermost tier of the evaporator chambers 5.

35 The distributor 30 has a plurality of partitions 36 therein arranged one above the other and extending outwardly and upwardly into the distributor at an angle to provide a plurality of superimposed pockets 37, the uppermost of which is located inwardly and directly below the inlet for liquid refrigerant into the distributor 30 from 40 the pipe 33. As the liquid refrigerant accumulates in the uppermost pocket 34, it will spill over the upper edge of the uppermost parts 36 into the pocket 37 therebelow. The various pockets are connected by supply pipes 38 to the various 45 evaporator chambers 5' in the respective tiers. Gas off-take pipes 39 extend from the evaporator chambers 5' into the distributor and extend across the upper edges of the respective partitions 36. The partitions 36 extend only partly across the 50 interior of the distributor 30, leaving a space or passage indicated at 40 through which the evaporated refrigerant may pass into the top of the distributor 30.

55 The distributor 30 is placed at an angle to the vertical so as to insure the spilling or overflow of the liquid refrigerant from one pocket 37 into the pocket next therebelow and also so that any condensation of the evaporated liquid refrigerant will fall in the various pockets.

60 It will be understood that the invention is not

to be limited to the specific construction or arrangement of parts shown but that they may be modified within the invention defined by the claims.

What is claimed is:

1. In a chilling apparatus, a conduit for conducting liquid to be treated comprising a plurality of vertically spaced pipe sections arranged in serially connected superposed tiers, evaporator jackets individual to said horizontal pipe 10 sections and forming evaporator chambers about the pipe sections, a distributor for delivering liquid refrigerant to said refrigerant chambers, and means in said distributor individual to each tier of evaporator chambers for controlling the 15 level of refrigerant in the evaporator chambers.

2. In a chilling apparatus, a conduit for conducting liquid to be treated comprising a plurality of vertically spaced pipe sections arranged in serially connected superposed tiers, evaporator 20 jackets individual to said horizontal pipe sections and forming evaporator chambers about the pipe sections, a distributor for delivering liquid refrigerant to said refrigerant chambers, means in said distributor individual to each tier 25 of evaporator chambers for controlling the level of refrigerant in the evaporator chambers, said means comprising overflow means controlling the delivery of liquid refrigerant from one of said individual means to the one next therebelow. 30

3. In a chilling apparatus, a conduit for conducting liquid to be treated comprising a plurality of vertically spaced pipe sections arranged in serially connected superposed tiers, evaporator 35 jackets individual to said horizontal pipe sections and forming evaporator chambers about the pipe sections, a distributor for delivering liquid refrigerant to said refrigerant chambers, means in said distributor individual to each tier of evaporator chambers for controlling the level of 40 refrigerant in the evaporator chambers, and means controlled by the level of liquid refrigerant in the lowermost tier of evaporator chambers for controlling the delivery of refrigerant to said distributor. 45

4. In a chilling apparatus, a conduit for conducting liquid to be treated comprising a plurality of vertically spaced pipe sections arranged in serially connected superposed tiers, evaporator 50 jackets individual to said horizontal pipe sections and forming evaporator chambers about the pipe sections, a distributor for delivering liquid refrigerant to said refrigerant chambers, means in said distributor individual to each tier of evaporator chambers for controlling the level of 55 refrigerant in the evaporator chambers, and an accumulator at the top of said distributor and open to the interior of the distributor for receiving gaseous refrigerant therefrom.

5. In a chilling apparatus, a conduit for conducting liquid to be treated comprising a plurality of vertically spaced pipe sections arranged in serially connected superposed tiers, evaporator 60 jackets individual to said horizontal pipe sections and forming evaporator chambers about the pipe 65 sections, a distributor for delivering liquid refrigerant to said refrigerant chambers, and means in said distributor individual to each tier of evaporator chambers for controlling the level of refrigerant in the evaporator chambers, the interior of said distributor provided with gas escape passages to permit gaseous refrigerant to 70 pass to the top of the distributor.

6. In a chilling apparatus, a conduit for conducting liquid to be treated comprising a plu- 75

rality of vertically spaced pipe sections arranged in serially connected superposed tiers, evaporator jackets individual to said horizontal pipe sections and forming evaporator chambers about the pipe sections, a distributor for delivering liquid refrigerant to said refrigerant chambers, means in said distributor individual to each tier of evaporator chambers for controlling the level of refrigerant in the evaporator chambers, means controlled by the level of liquid refrigerant in the lowermost tier of evaporator chambers for controlling the delivery of refrigerant to said distributor.

7. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said refrigerant chambers, means in said distributor individual to each tier of evaporator chambers for controlling the level of refrigerant in the evaporator chambers, and an accumulator at the top of said distributor and open to the interior of the distributor for receiving gaseous refrigerant therefrom, the interior of said distributor provided with gas escape passages to permit vaporized refrigerant to pass to the top of the distributor.

8. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said evaporator chambers, vertically spaced partitions in said distributor forming a liquid refrigerant containing pocket for each tier of evaporator chambers, connections between said pockets and chambers for delivering liquid refrigerant to said chambers whereby the level of liquid refrigerant in said pockets will control the level of liquid refrigerant in said evaporator chambers.

9. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said evaporator chambers, vertically spaced partitions in said distributor forming a liquid refrigerant containing pocket for each tier of evaporator chambers, connections between said pockets and chambers for delivering liquid refrigerant to said chambers whereby the level of liquid refrigerant in said pockets will control the level of liquid refrigerant in said evaporator chambers, and gas escape pipes opening from said chambers into said distributor, the interior of said distributor provided with gas escape passages to permit vaporized refrigerant to pass to the top of the distributor.

10. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said evaporator chambers, vertically spaced partitions in said distributor forming a

liquid refrigerant containing pocket for each tier of evaporator chambers, connections between said pockets and chambers for delivering liquid refrigerant to said chambers whereby the level of liquid refrigerant in said pockets will control the level of liquid refrigerant in said evaporator chambers, gas escape pipes opening from said chambers into said distributor, the interior of said distributor provided with gas escape passages to permit vaporized refrigerant to pass to the top of the distributor, and means controlled by the level of liquid refrigerant in the lowermost tier of evaporator chambers for controlling the delivery of refrigerant to said distributor.

11. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said evaporator chambers, vertically spaced partitions in said distributor forming a liquid refrigerant containing pocket for each tier of evaporator chambers, overflow pipes carried by said partitions for controlling the level of refrigerant in said pockets and whereby refrigerant will pass successively from one pocket to the pocket next therebelow.

12. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said evaporator chambers, vertically spaced partitions in said distributor forming a liquid refrigerant containing pocket for each tier of evaporator chambers, overflow pipes carried by said partitions for controlling the level of refrigerant in said pockets and whereby refrigerant will pass successively from one pocket to the pocket next therebelow, an accumulator at the top of said distributor and open to the interior of the distributor for receiving vaporized refrigerant therefrom.

13. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe sections, a distributor for delivering liquid refrigerant to said evaporator chambers, vertically spaced partitions in said distributor forming a liquid refrigerant containing pocket for each tier of evaporator chambers, overflow pipes carried by said partitions for controlling the level of refrigerant in said pockets and whereby refrigerant will pass successively from one pocket to the pocket next therebelow, an accumulator at the top of said distributor and open to the interior of the distributor for receiving vaporized refrigerant therefrom, and gas escape pipes carried by said partitions and opening from one chamber into the chamber next thereabove whereby vaporizing refrigerant may pass through the distributor to said accumulator.

14. In a chilling apparatus, a conduit for conducting liquid to be treated comprising a plurality of vertically spaced pipe sections arranged in serially connected superposed tiers, evaporator jackets individual to said horizontal pipe sections and forming evaporator chambers about the pipe

sections, a distributor for delivering liquid refrigerant to said evaporator chambers, vertically spaced partitions in said distributor forming a liquid refrigerant containing pocket for each tier of evaporator chambers, overflow pipes carried by said partitions for controlling the level of refrigerant in said pockets and whereby refrigerant will pass successively from one pocket to the pocket next therebelow, an accumulator at the top of said distributor and open to the interior of the distributor for receiving vaporized refrigerant

erant therefrom, gas escape pipes carried by said partitions and opening from one chamber into the chamber next thereabove whereby vaporizing refrigerant may pass through the distributor to said accumulator, and means controlled by the level of liquid refrigerant in the lowermost tier of evaporator chambers for controlling the delivery of refrigerant to said distributor. 5
